UNITED STATES PATENT OFFICE

146,276

DESIGN FOR A PIN OR SIMILAR ARTICLE

Marcel Boucher, New York, N. Y.

Application December 27, 1945, Serial No. 125,052

Term of patent 7 years

(Cl. D45—19)

To all whom it may concern:

Be it known that I, Marcel Boucher, a citizen of the United States, residing in New York city, in the county of New York and State of New York, have invented a new, original, and ornamental Design for a Pin or Similar Article, of which the following is a specification, reference being had to the accompanying drawing, forming part thereof.

Fig. 1 is a front elevational view of a pin or similar article, showing my design, and

Fig. 2 is the side view thereof.

The characteristic feature of my design for a bowknot pin resides in the combination of the large and small round stones and faceted, oval-shaped stones forming the semicircular center thereof in association with the double looped bow, all as shown.

I claim:

The ornamental design for a pin or similar article, substantially as shown and described.

MARCEL BOUCHER.
